A. B. CLARK.

PHONOGRAPH ATTACHMENT FOR TELEPHONE CIRCUITS.

(Application filed July 10, 1900.)

(No Model.)

UNITED STATES PATENT OFFICE.

ALLAN B. CLARK, OF NASHVILLE, TENNESSEE, ASSIGNOR OF ONE-HALF TO
J. ROY BOONE, OF SAME PLACE.

PHONOGRAPH ATTACHMENT FOR TELEPHONE-CIRCUITS.

SPECIFICATION forming part of Letters Patent No. 667,503, dated February 5, 1901.

Application filed July 10, 1900. Serial No. 23,151. (No model.)

To all whom it may concern:

Be it known that I, ALLAN B. CLARK, a citizen of the United States, residing at Nashville, county of Davidson, State of Tennessee, have invented certain new and useful Improvements in Phonograph Attachments for Telephone-Circuits, of which the following is a specification.

My invention relates to means for conveying phonographic messages over telephone-circuits; and my object is to provide a phonograph attachment to a telephone-circuit which will transmit messages—such as advertising matter, news matter, &c.—to different subscribers from a central station without interfering with the conversation between subscribers or the operation of the line by the operators at the central station.

With this object in view my invention consists in the means for automatically causing the transmission of phonographic messages to a subscriber on a telephone-circuit independently of any act of the central operator while the subscriber is waiting to be connected with a given line through a central station and in means for cutting off the phonograph-circuit at the same time that the operator at the central station connects the subscriber with central or with the line asked for by said subscriber.

In the drawing I have shown a diagrammatic view illustrating my invention as applied at a central station, using for the purpose of illustration three subscribers' lines.

Referring to the drawing, the numeral 1 indicates a phonograph-record, which is continuously operated in the usual manner, having thereon the messages to be conveyed over the various lines, said messages constituting advertising matter, which it is desired to communicate in the manner hereinafter described.

The numeral 2 indicates the granular carbon button of the phonograph-transmitter, which is connected with the usual diaphragm carrying the stylus 3, that travels in the record-path of the cylinder. I connect this phonograph with the ground or common return wire 8 of the switchboard at the central station by the wires 6 and 7 and through the battery 5 and the induction-coil 4, the said induction-coil operating in the usual manner

of said coils to convey the impulses received from the phonograph through the wire 17, with which are connected branch wires 18 55 18' 18², leading to the drop-signals 15 15' 15² on the switchboard and the several subscribers' wires 16 16' 16².

For each subscriber's wire is provided an ordinary spring-jack 14 14' 14², which normally connects the subscriber's line with the phonograph-circuit, as shown on the line 16², whereon the spring-jack 14² is in contact with its contact-point, thus completing the circuit through the induction-coil and phonograph. 65

Each subscriber's line of course is connected with the ground or common return wire 8 of central station. The operator's set is indicated diagrammatically by the numeral 9, the numeral 10 indicating the switch-button controlled and operated by the operator when a signal is made by a given drop, indicating a call in the usual way. 70

The numerals 12 and 12' indicate switch-plugs, each having a projection 13 13', which projection is adapted to be inserted between the contact-springs of the spring-jack in the manner shown in the drawings in order to connect the central with the subscriber who makes a call, the operator using two plugs, 80 as shown in the drawing, in order to connect any two given subscribers who desire to converse.

As shown in the drawing, two subscribers at A A' are connected through the wires 16 85 16', spring-jacks 14 14', plugs 12 12', and the connecting-wires 11 11'.

It will be observed that when a plug is inserted in the switchboard at central the corresponding spring-jack will be moved, thereby breaking the connection between the subscriber and the phonograph-circuit. At the same time such insertion of the plug will connect the subscriber on that line with the operator, who receives the message and then calls up the subscriber desired, inserting a plug in the switchboard at the proper point for connecting the two subscribers who desire to converse. Before the insertion of the plug by the operator it will be observed that the subscribers' lines are normally connected with the phonograph-circuit, so that the moment any subscriber takes down his receiver and places it to his ear he will hear the message 95 100

or messages transmitted from the phonograph-record, which operates continuously, and will continue to hear such messages until the operator inserts a plug at the switchboard in response to the drop-signal made when the subscriber calls, and the moment central responds the subscriber ceases to hear the phonograph message or messages, thereby preventing any interference whatever with the operation of the telephone system. It will be observed also that at no time is the operator connected with the phonograph-circuit, so that there is no possible interference with the usual operation of the telephone-circuit at central, and, further, that the transmission of the phonographic messages in no wise depends on any act of the operator, nor is he required to perform any special act in addition to the usual manipulation of the switch-plugs connecting the different subscribers who desire to converse. It should also be noted that the phonograph need not be located at central, as it may obviously be placed in the subscriber's office for the transmission of messages from such office to central or to any other subscriber in the same circuit, the essential requirement being that the phonograph shall be normally in circuit with the subscribers' lines whenever it is desired to send a message by means of the phonograph over said lines.

By the term "phonograph" as used in the specification and claims I intend to cover any form of talking or sound-reproducing machine capable of use in the relation shown and described.

I am aware that it is old to connect a phonograph-record with a telephone-circuit at central in order to convey a message to a given subscriber that a given line is "busy;" but in such devices with which I am familiar the operator is required to insert by one movement what is called the "busy-plug" in order to connect the phonograph with the subscriber, which remains in position until the operator is informed that the line desired is not busy, whereupon he is required to remove the said plug and then connect the two subscribers together by means of the usual plugs or switches. My invention differs from this and prior devices of like nature in that the phonograph operates continuously and conveys its messages to the subscribers the moment the receiver is removed and placed to the ear and central is called and continues to deliver such messages until the operator at central responds, whereupon the phonograph is disconnected without any special act on the part of the operator at central beyond the usual operation of connecting central with the subscribers.

Without, therefore, claiming broadly the combination of a phonograph with a tele-

phone-circuit, what I do claim as my invention, and desire to secure by Letters Patent of the United States, is—

1. The combination with a central station of a telephone-circuit and subscribers' lines connected thereto, of a phonograph normally in circuit with said subscribers' lines, and means controlled by the operator, at central, for connecting with a given subscriber and at the same time disconnecting said phonograph from said subscriber, substantially as described.

2. The combination with a central station of a telephone-circuit and subscribers' lines connected thereto, of a phonograph, normally in circuit with different subscribers, spring-jacks for each subscriber's line at the central station, and a plug adapted to be inserted so as to release said spring-jacks, and break the connection between the phonograph and the subscriber while connecting the subscriber with central or with another subscriber through central, substantially as described.

3. The combination of the central station of a telephone system, subscribers' lines connected thereto and a common return for the same, with a phonograph, an induction-coil in circuit therewith and connected with the common return at the central station, and a wire connecting the induction-coil with the subscribers' lines at each station, a spring-jack in each subscriber's line normally connecting it to the phonograph-circuit, and a plug adapted to be inserted by the operator to move the spring-jack so as to break the connection between the subscriber's wire and the phonograph, substantially as described.

4. The combination with a central station of a telephone-circuit and subscribers' lines connected thereto, of a phonograph normally in circuit with said subscribers' lines, an operator's set disconnected from said phonograph and means controlled by a single movement of the operator at the central station for disconnecting the phonograph from a given subscriber when the latter is connected with a given line, substantially as described.

5. The combination with a central station of a telephone system and subscribers' lines connected thereto, of a phonograph normally in circuit with the subscribers' lines and means for connecting any two subscribers with each other and simultaneously disconnecting said phonograph from said subscribers.

In testimony whereof I have signed my name to this specification in the presence of two subscribing witnesses.

ALLAN B. CLARK.
